UNITED STATES PATENT OFFICE

JOHN B. SUNT, OF RHINELANDER, WISCONSIN

POSITION-INDICATING AND AIR-SUPPLYING DEVICE FOR SUNKEN SUBMARINES

Application filed March 19, 1928. Serial No. 262,905.

This invention relates to means for indicating the position of a sunken submarine and for supplying air to the interior of the submarine so that the usual salvage operations 5 may be performed without danger of loss of life to the submarine crew even though a week or more may be required in bringing the ship to the surface.

An important object of the invention re- 10 sides in the provision of a device of this character that is of very simple construction and which may be incorporated as a part of the submarine during the building thereof or that may be installed in submarines now in 15 use.

Generally the invention consists in providing the opposite sides of the ship with compartments, that are normally closed, and within which are buoys that will float to the 20 surface of the water when the compartments have been opened, said buoys being attached to the submarine by cables, said buoys identifying the location of the sunken ship and permitting air to be taken therethrough 25 and through air hoses connected therewith at their outer ends, the inner ends of said hoses having communication with the interior of the ship.

In the drawings: 30 Figure 1 is a side elevation of a submarine on the surface of the water equipped with my improved locating and air supplying devices.

Figure 2 is a similar view of a submerged submarine, the buoys of the invention being 35 upon the surface of the water for identifying the location of the ship and to permit air to be conveyed to the ship,

Figure 3 is a fragmentary vertical section 40 through one of the ship sides constructed of a normally closed compartment that may be opened from the interior of the ship and within which compartment is a pair of buoys for floating to the water surface when the compartment is opened,

Figure 4 is a horizontal section taken 45 through one of the compartments of the ship,

Figure 5 is a fragmentary section through the bottom wall of one of the buoys equipped 50 with means for permitting communication

between the salvaging ship and the sunken submarine,

Figure 6 is a detail section through the air supplying buoy,

Figure 7 is a fragmentary section through 55 the upper end of the buoy the inlet end of the air passage being equipped with an air inlet cap and

Figure 8 is a perspective of one of the 60 position indicating buoys.

Now having particular reference to the drawings A designates generally a conventional submarine. In carrying out my invention the opposite sides of the submarine are constructed with compartments 5 each 65 of which is open at its outer side as disclosed clearly in Figures 3 and 4.

Mounted within the open outer side of 70 each compartment is a pair of vertically arranged swinging doors 6-6. These doors are so mounted with respect to the compartment that they have to be opened inwardly 75 of the compartment as disclosed by the arrows in Figure 4. The adjacent vertical edges of these doors are formed with flanges 6'-6', the edges of which are formed at opposite sides to the center with notches 7, the outer edges of which are beveled as clearly disclosed in Figure 3. Pivoted to the top and bottom walls of the compartment and interiorly 80 thereof are arms 8-8 to the outer end of which are pivoted extensions 9-9 adapted for engagement within the said notches 7-7 of the door flanges when the doors have been swung to closed position. 85 Pivoted within said slots formed in said arms 8-8 are threaded collars 10-10 through which are threaded bolts 11-11 that extend through the top and bottom walls of the compartment as disclosed.

Keyed to the inner ends of said bolts 11-11 90 are beveled gears 12-12 that have mesh with similar beveled gears 13-13 keyed upon the inner ends of horizontal shafts 14-14 the inner ends of which are journaled through openings in the inner wall of the submarine, the extreme inner end thereof being equipped with turning wheels 15-15. Obviously when 95 it is desired to open the doors 6-6 from the interior of the submarine the wheels 15-15 100

are rotated for causing the rotation of the bolt 11—11 for drawing the arms 8—8 as well as their extensions 9—9 toward the top and bottom walls of the compartment which will break the joint between the arms and the extension whereupon the doors will automatically open due to the pressure of the water when the submarine is in submerged condition as disclosed in Figure 2.

Within each compartment is a pair of barrel shaped buoys 16 and 17 arranged in side by side relation within the inner wall of the submarine as clearly disclosed in Figure 4. The pair of buoys in each compartment are connected to the opposite ends of a relatively great length of cable 18 which cable is trained over a horizontal bar 18' anchored within the compartment, and as soon as the doors 6 have been opened the water rushing into the compartment will cause the floating of the buoys whereupon they will be guided to the open side of the submarine by the doors 6—6 eventually floating to the surface of the water as indicated in Figure 2. The buoys 16 are for the purpose of identifying the location of the submerged ship while the other buoys 17 are provided for the purpose of permitting air to reach the interior of the sunken submarine. By detaching one of the buoys from the end of the cable 18 a hoisting chain may be attached to the cable and thence by pulling upwardly on the end of the cable attached to the other buoy the chain may be engaged around the bar 18' so as to enable the salvaging ship to raise the submarine.

Each buoy 17 is constructed with a longitudinal air pipe 19, the lower end of which has communication with an air hose 20 that communicates at its opposite end with the interior of the submarine as disclosed in Figure 3. Liquid food may also be conveyed to the submarine crew through this air hose.

The outer end of the air pipe 19 projects through the top wall of the buoy and is threaded for the reception of a cap 23 which cap is of cylindrical formation and formed at its sides with air inlet openings 24 so as to permit the air to pass into the pipe. This buoy will rise so rapidly through the water that the small amount of water passing through the openings into the pipe 19 and hose 20 will be negligible.

As clearly disclosed in Figures 6 and 7 the side wall of the buoy 17 extends above the top wall thereof so as to prevent the water from flowing into the openings 24. Said side wall of the buoy directly above the top wall is formed with water outlet openings 25 so that the water cannot collect in the space above said top wall.

The bottom wall of each buoy 17 is formed with a threaded pocket 36 within which is normally arranged a bell or cylinder 27 within which is arranged a telephonic instrument 28 to which is attached an electric wire 29

that communicates at its opposite end to a suitable telephonic instrument within the interior of the submarine so that conversation may be held between the submarine crew and the crew of the salvaging ship.

In view of the foregoing description when considered in conjunction with the accompanying drawings, it will be apparent that I have provided a highly novel, simple and extremely useful position indicating and air supplying device for sunken submarines and herein I have shown and described the invention consisting of certain detail structural elements but nevertheless it will be understood that some changes may be made therein without affecting the spirit or scope of the appended claims.

It is obvious that my invention is susceptible to various changes and modifications in construction without departing from the spirit of the invention or the scope of the appended claim, and I accordingly claim all such forms of the device to which I am entitled.

Having thus described my invention, what I claim as new is:

In a means for supplying air to the interior of a sunken submarine, a buoy normally attached to the submarine and adapted to float to the surface when released from the submerged vessel, said buoy comprising top and bottom walls, and an interconnecting side wall, the upper edge of the side wall projecting above the top wall, the upper portion of the side wall directly above the top wall being formed with water outlet openings, an air pipe extending through the top and bottom walls, the upper end providing an air inlet and projecting above the water outlet openings in the side wall, a cylindrical cap secured at its lower end on the upper end of the air pipe, the top of the cap being closed, the side of the cap above the upper end of the air pipe being formed with air inlet openings, and a hose affording communication between the lower end of the air pipe and the interior of the sunken submarine.

In testimony whereof I affix my signature.

JOHN B. SUNT.
